CEILING RUNNER

Howard A. Busby, 6361 Rancho Park Drive, San Diego,
Calif. 92120, and Paul D. Dail, 800 S. Sunset, West
Covina, Calif. 91790

Filed June 5, 1970, Ser. No. 23,333

Term of patent 14 years

Int. Cl. D25—01

U.S. Cl. D13—1

FIG.1

FIG.2

FIG.3

FIG.4

FIG.5

FIG.6

FIG. 1 is a perspective view of a ceiling runner showing our new design;

FIG. 2 is a broken vertical sectional view taken along the line 2—2 of FIG. 1;

FIG. 3 is a broken top view of the ceiling runner shown in FIG. 1;

FIG. 4 is a broken bottom view of the ceiling runner shown in FIG. 1;

FIG. 5 is a vertical elevational view of the right end of the ceiling runner shown in FIG. 1; and

FIG. 6 is a vertical elevational view of the left end of the ceiling runner shown in FIG. 1.

We claim:

The ornamental design for a ceiling runner, substantially as shown.
